UNITED STATES PATENT OFFICE.

WILLIAM J. CUNNINGHAM, OF PHILADELPHIA, PENNSYLVANIA.

MACHINE FOR WASHING OR STERILIZING BOTTLES.

SPECIFICATION forming part of Letters Patent No. 697,201, dated April 8, 1902.

Application filed June 8, 1901. Serial No. 63,733. (No model.)

To all whom it may concern:

Be it known that I, WILLIAM J. CUNNINGHAM, a citizen of the United States, residing in the city and county of Philadelphia, State 5 of Pennsylvania, have invented a new and useful Improvement in Machines for Washing or Sterilizing Bottles, of which the following is a specification.

My invention consists in an improvement 10 in a machine for washing or sterilizing bottles; and it consists in subjecting the bottle to the action of various cleansing, sterilizing, or other solutions in regular succession.

It further consists of an endless belt or conveyer having means thereon for sustaining 15 the bottle.

It further consists of the novel holder for the said bottle and means for opening and closing the same.

20 It further consists of novel details of construction, all as will be hereinafter set forth.

Figure 1 represents a vertical sectional view of a machine embodying my invention. Fig. 2 represents a plan view thereof, showing 25 the hood employed in dotted line. Fig. 3 represents a sectional view on line $\alpha\alpha$, Fig. 2. Fig. 4 represents a side elevation of a portion of the machine, showing a portion of the device for opening the bottle-holder. Fig.

30 5 represents a perspective view of the bottle-holder on an enlarged scale. Fig. 6 represents a side elevation of a bottle-holder, showing the bottle in position. Fig. 7 represents a perspective view of a machine, showing a 35 slightly-different manner of mounting the conveyer.

Similar numerals of reference indicate corresponding parts in the figures.

Referring to the drawings, 1 designates a 40 bottle washing or sterilizing machine consisting of a tank 2, which in the present instance is divided into compartments 3, 4, and 5, which are adapted to contain suitable cleansing solutions or material. For example, in 45 compartment 3 I will use potash, in compartment 4 steam, and in compartment 5 water, the compartment 3 being provided with an outlet 6, which is closed by a pipe 7, the upper end of which is opened in order to prevent 50 an overflow, while the compartment 4 is provided with a steam-inlet 8 and the com-

partment 5 with an outlet 9, having a pipe 10 for the same use as pipe 7.

Mounted in the sides of the tank 2 is a shaft 11, which is supplied with beaters 12, situated in the compartments, said shaft 11 having a gear 13 thereon, which meshes with a gear 14, to which power is imparted by the shaft 15, carrying a pulley 16 for a belt. Also mounted in the walls of the tank 2 are the 60 shafts 17, 18, 19, and 20, each of which is provided with a plurality of wheels or pulleys 21, which are situated at proper angles. Suitably mounted upon the walls of the tank 2 are the wheels or pulleys 22, 23, and 24. 65

25 designates a table or shelf, suitably supported on which is the guide 26, having the inclined ends 27 and 28, said table 25 carrying a roller 29.

30 designates a hood which is suitably supported and covers the compartment 4 and having the sides which extend into the compartments 3 and 5, as best seen in Fig. 1, a suitable space being left between the said sides and the walls 31 and 32, which form the 75 compartments. Within said hood is a shaft 33, which is suitably journaled in standards 34, said shaft having thereon the pulleys or wheels 35 and 36 and also the wheels 37.

38 designates an endless chain or conveyer, 80 which in the present instance is formed of suitable links and is adapted to pass, for example, around the pulley 22 and around the pulleys 21, mounted on the shafts 17, 18, 19, and 20 in the compartment 3. When it reaches 85 the last of these pulleys, it passes up into the hood 30 over the pulley 35 and then down into the compartment 4, around the pulleys 21 on the shafts and up over the pulleys 37 until it reaches the pulley 36, when it will 90 pass down into compartment 5 and around the pulleys 21 on the shafts until it reaches the pulley 23, when the chain will be outside of the tank, as seen in the right of Fig. 2. It then passes around pulley 29 back to 22. 95

Referring now to Figs. 5 and 6, I will explain the construction of the bottle-holder, it being seen that each of the links of the chain is provided with one holder for the reception of a bottle. 39 designates one of the links, 100 to which is secured a block 40, which carries the springs 41 and 42, the normal position of

which is best seen in Fig. 6. It will be necessary in order to insert or remove a bottle therefrom to have the said springs open in the direction indicated by the arrows, said 5 springs being secured to the block 40 by the plates 43 and 44 and bolted thereto.

The operation is as follows: Suitable cleansing materials are placed in the compartments and power is applied to the machine, which 10 causes the various shafts to revolve. This carries with it the endless chain, which takes the course above described, carrying with it the bottle-holder, only a few of which I have indicated in the drawings in order not to 15 overcrowd the same. When the bottle-holders reach the inclined face 27 of the guide 26, the point of said face passes between the ends of the springs 41 and 42, and in the continued forward movement of the chain the ends of 20 the springs will reach the widened portion of the guide and assume the position seen in the left of Fig. 3, so that if a bottle can be carried by said holder the same could be easily removed by the operator and another 25 bottle inserted, the springs resuming their novel position and grasping the bottle when the inclined face 28 of the guide is reached. The bottle will now be carried by the chain or conveyer, and under the circumstances 30 above described will be first thoroughly washed by the potash, then by the steam, and lastly by the water. It will be seen that by this means a very large number of bottles can be washed or sterilized or both washed and 35 sterilized in a quick and thorough manner. By reason of the sides of the hood extending into the compartments 3 and 5 and when the same are filled with a liquid to a point above the lower edge of said sides the same will 40 form a steam-trap, but will permit the bottle to pass from one compartment to the other and to be subjected to the various cleansing agents. It will also be evident that the 45 guide 26 can be placed at any desired distance or point from the rest of the machine, it only being necessary to extend the chain thereto.

In Fig. 7 I have shown a construction wherein I employ a number of suitable shafts suitably mounted, the same carrying sprocket-wheels and around which a chain is adapted to pass in a different manner from that shown in Figs. 1 and 2, as in this case I have caused the chain to travel a different direction 55 through the tank instead of sidewise or from side to side and passing lengthwise, and employ the same bottle-holders and means for opening and closing the same. In this figure the movement of the chain from the sprocket-60 wheel 45, for example, moves in the direction of the arrow and will pass down through the sprocket 46, then around the sprocket 47, up over sprocket 48, around sprocket 49, down and around sprocket 50, around sprocket 51, 65 and up over sprocket 52, it then passing out of the compartment or tank and over the sprocket 53, whence it passes directly to the

opposite end of the tank and around sprocket 54, and thence around sprocket 55, down and around sprocket 56, around sprocket 57, over 70 sprocket 58, around sprocket 59, and down and around sprocket 60, over sprocket 61, and up to sprocket 62, whence it will pass to the opposite end of the tank back of the sprocket 45. The operation of this construction will be the same as previously described, 75 it being of course evident that in both instances it can be divided into compartments or not, as desired.

It will be apparent that various changes 80 may be made by those skilled in the art which will come within the scope of my invention, and I do not therefore desire to be limited in every instance to the exact construction herein shown and described.

Having thus described my invention, what I claim as new, and desire to secure by Letters Patent, is—

1. In a machine of the character named, a tank adapted to contain a suitable material 90 for cleansing or sterilizing, or both cleansing and sterilizing, and means for causing a bottle to traverse said tank up and down and from side to side through said material.

2. In a machine of the character named, a 95 tank adapted to contain suitable cleansing or sterilizing material, an endless chain or conveyer passing through said tank up and down and transversely thereof and means for holding a bottle on said conveyer.

3. In a machine of the character named, a tank, a plurality of compartments therein adapted to contain cleansing or sterilizing material, an endless chain or conveyer passing from one compartment to the other, devices 105 for holding a bottle carried by said conveyer, and means for opening and closing said devices for the insertion and removal of the bottle.

4. In a machine of the character named, a 110 tank, a plurality of compartments therein adapted to contain cleansing or sterilizing material, pulleys suitably supported in said compartment, and an endless chain or conveyer around said pulleys and passing from one 115 compartment to the other and adapted to carry bottles thereon.

5. In a machine of the character named, a tank adapted to contain suitable cleansing or sterilizing material, shafts journaled in said 120 tank, pulleys on said shafts, an endless chain or conveyer adapted to pass around said pulleys, agitators in said tank, and means for operating said agitators.

6. In a machine of the character named, an 125 endless chain or conveyer in combination with a bottle-holder on said chain, consisting of spring-arms suitably supported and a guide which passes between said spring-arms to open the same.

7. In a machine of the character named, a 130 tank, compartments therein, a hood over one of said compartments, shafts in said compartments carrying pulleys, an endless belt

or conveyer adapted to pass around said pulleys, bottle - holders on said conveyer, and means for opening and closing said bottle-holders.

5 8. In a machine of the character named, a bottle-holder consisting of a block and spring-arms secured thereto, and a guide which passes between said spring-arms to open the same.

10 9. In a machine of the character named, a tank, adapted to contain a suitable cleansing or sterilizing material, and a hood over said tank adapted to prevent the escape of said material, and means for causing a bottle to 15 traverse said tank in said material.

10 10. In a machine of the character named, a tank, compartments therein, a hood for one of said compartments arranged to form in the walls thereof a steam-trap, and permitting 20 the entrance of a bottle into said hood and compartment.

11. In a machine of the character named, a tank adapted to contain suitable cleansing or sterilizing material, pulleys in said tank and 25 endless chain or conveyer adapted to pass around said pulleys, agitators in said tank and means for operating said agitators.

12. In a machine of the character named, a plurality of tanks, a steam-trap for one of 30 said tanks, and an endless chain or conveyer

passing through said tanks and said steam-trap.

13. In a machine of the character named, a plurality of tanks adapted to contain suitable cleansing or sterilizing material, a hood over 35 one of said tanks adapted to form a steam-trap, and means for causing a bottle to pass from one tank to the other and into said tank beneath the hood.

14. In a machine of the character named, a plurality of tanks adapted to contain suitable cleansing or sterilizing material, an endless chain or conveyer adapted to pass from one tank to the other through said material, devices for holding a bottle carried by said conveyer, and means for opening and closing devices for the insertion and removal of the bottles. 45

15. In a machine of the character named, a plurality of tanks, adapted to contain suitable 50 cleansing or sterilizing material, an endless chain or conveyer adapted to pass through said tanks, and from one to the other, agitators in said tanks, and means for operating said agitators.
